DESIGN FOR A COMBINED CLOCK AND PICTURE HOLDING CASE

Henry Sochard, Brooklyn, N. Y.

Application April 22, 1940, Serial No. 91,858

Term of patent 3½ years

To all whom it may concern:

Be it known that I, Henry Sochard, a citizen of the United States, and resident of Brooklyn, New York, in the county of Kings and State of New York, have invented a new, original, and ornamental Design for a Combined Clock and Picture Holding Case, of which the following is a specification, reference being had to the accompanying drawing, forming a part thereof, and of which Figure 1 is a perspective view in closed position of a combined clock and picture holding case showing my new design, Fig. 2 is a view in front elevation in open position, Fig. 3 is a corresponding view thereof in end elevation, and Fig. 4 is a corresponding perspective rear view thereof.

I claim:

The ornamental design for a combined clock and picture holding case, substantially as shown.
HENRY SOCHARD.
